UNITED STATES PATENT OFFICE.

LOUIS LEMOINE, OF PARIS, FRANCE, ASSIGNOR TO SOCIÉTÉ ANONYME D'APPLICATIONS DES GAZ LIQUÉFIÉS, OF PARIS, FRANCE, A LIMITED JOINT-STOCK COMPANY OF FRANCE.

DEVICE FOR CLOSING COMPRESSED OR LIQUID GAS CYLINDERS.

Application filed March 8, 1923. Serial No. 623,605, and in France April 20, 1922.

My invention relates to devices for closing cylinders containing compressed or liquefied gas.

Cylinders for compressed or liquefied gas as illustrated in Fig. 1 of the accompanying drawings at 1, are already known. Such cylinders are closed by a stopper cap 3 screwed on their open end 2 and thus forming a joint at this end by the action of the pressure directed from the outside towards the interior of the cylinder; a washer of plastic material 4 is usually interposed between the stopper 3 and the mouth of the cylinder.

In the arrangement illustrated in Fig. 1 the body of the cylinder is made in one piece, but it may be of advantage to make it in two parts for two reasons. The first reason is that the open end having to be brought down to a very small diameter, in order to reduce to a practical minimum the joint there formed and the strain to be exerted on the stopper 3 in order to obtain the tightness of the joint, the work of drawing out the cylinder is long and difficult and consequently costly. The second reason is that the open end of the cylinder, thus reduced to a very small internal diameter, is easily stopped up by foreign bodies (rust or the like) which may be formed inside the cylinder and which it is impossible to remove therefrom.

The well known arrangement shown in Fig. 1 may therefore be modified as shown in Fig. 2. In this modified cylinder the cylinder is formed of a body part proper 1 and an added portion 9 screwed thereon in such a way as to form a tight joint and terminating at its free end in a reduced portion, that is to say having a reduced internal diameter which is threaded externally in order to receive the cap 3. This arrangement avoids the two disadvantages hereinbefore mentioned because it dispenses with continuing the work of drawing out to the extreme end of the body of the cylinder, and in case of the obstruction of the passage, the unscrewing of the part 9 enables foreign matters which may be found in the body of the cylinder to be easily removed.

Both the foregoing types of cylinders however which are already known have two essential disadvantages.

Firstly, the cap 3 must be screwed on only moderately tightly where the same plastic washer 4 is to serve for successive recharging of the cylinder, that is to say, in the case where the discharge of the contents is obtained not by perforation of the closing member but by unscrewing the cap 3. The result is that the cap 3 easily becomes unscrewed by the action of vibration. This cap must also normally be unscrewed during the use of the cylinders. Consequently, as no holding arrangement exists, this cap 3 may become entirely separated from the cylinder and be lost leaving the interior of the cylinder exposed to external agencies.

In addition to this, both for the refilling and discharging the contents of the cylinder respectively from and into a closed receptacle under pressure, a tight joint must be provided between the cylinder and the said receptacle, and this joint must be arranged on the neck 5 of the cylinder; consequently this joint has necessarily a relatively large diameter and requires in order to produce a tight joint an effort proportional to its dimensions. Further, this joint is arranged at a point which is somewhat distant from the end of the cylinder which is inconvenient for inserting the cylinders in the charging and using apparatus and for their subsequent removal from the said apparatus more particularly for those operations which must be done automatically. Finally, the joint must be made on a rounded surface which is not well adapted to produce a good tight fitting connection.

This invention relates to an arrangement for closing compressed or liquid gas cylinders whereby the disadvantages hereinbefore stated are avoided and which may be applied equally well to any of the types of cylinders hereinbefore described.

According to the present invention, an internally threaded socket is adapted to be screwed onto the neck of the cylinder, forming a tight joint therewith the free end of the said socket thus being adapted to serve also as a joint between the cylinder and a vessel under pressure. Moreover, the free end of the socket acts with its interior as an abutment for the closing cap thus preventing it from being completely unscrewed.

Various embodiments in accordance with this invention are illustrated as an example in the accompanying drawings, in which:—

Figs. 1 and 2 are longitudinal sections 5 through the old style cylinders above referred to.

Fig. 3 is a longitudinal section of a one-piece cylinder equipped with the new closing device,

10 Fig. 4 a longitudinal section of a modification of the construction shown in Fig. 3,

Fig. 5 a longitudinal section of a further modification of the foregoing cylinder,

15 Fig. 6 a longitudinal section of a two-piece cylinder equipped with the new closing device,

Fig. 7 a longitudinal section of a modification thereof, and

20 Fig. 8 a longitudinal section of another modification thereof

The cylinder 1 (Fig. 3) supports a socket 6 which is internally threaded and screwed on a corresponding thread on the neck of the cylinder. The screwing connection being 25 made tight enough, the socket 6 thus forms with the body of the cylinder, along an inclined annulus 7, a sufficiently tight joint with or without the interposition of a plastic packing material. The socket 6 has at its 30 free end a reduced internal diameter which is smaller than the external diameter of the cap 3 so that the latter cannot be completely unscrewed. The pitch of the respective threads of the socket 6 and the cap 3 may be 35 in the same direction or in opposite directions.

For recharging or discharging the cylinder, the joint between the latter and the pressure receptacle is obtained around the 40 extremity of the socket 6, or on the end plane of this socket, or by means of a stuffing box fitting on the cylindrical part 8. In both cases the joint is obtained on a surface of small diameter and at the end of the cylinder itself, or in proximity to this end.

As soon as the cylinder is charged and closed by the cap or stopper 3, the joint at 7 between the stopper 6 and the body of the cylinder is no longer of importance until the 50 moment of discharging the cylinder; an imperfect tightness of this joint has no influence on the tightness of the cylinder itself. It has only the inconvenience of a slight loss of gas when filling or discharging.

In the modification illustrated in Fig. 4 the joint between the socket 6 and the body 1 of the cylinder instead of being arranged at the inner end of the socket is obtained 60 by a shoulder 12 being formed on said socket at the end of the threaded portion and being forced against a corresponding shoulder on the body of the cylinder.

The arrangement which is shown in Fig. 65 5 dispenses with the thread of the cylinder

intended for the fitting of the stopper 3. This stopper is screwed into a thread on the socket 6. In Fig. 5 this thread is a prolongation of the thread which is formed on the cylinder but it may be a thread of 70 smaller diameter which allows of its being given a different pitch and one in an opposite direction.

Figure 6 is an arrangement of a body of a cylinder made in two parts of the type 75 shown in Figure 2 to wit, a cylindrical body part 1 and a neck part 9 and in which the socket 6 has the same characteristics as it has in Figure 5 and additionally that of connecting together the two parts 1 and 9 80 of the body of the cylinder. For this purpose the socket 6 is internally threaded at two different diameters, the larger one being formed on the body 1 of the cylinder and the smaller one serving for the screwing 85 of the stopper 3. Between these two threads an annular abutment 12 is provided by means of which when the socket 6 is screwed on the body of the cylinder 1 the part 9 is pressed against the cylindrical part 90 1, a disk of plastic material 11 being generally interposed; a tight connection of the two parts 1 and 9 is thus obtained, the whole of which forms the body of the cylinder. The annular joint 12 between the socket 6 and the member 9 corresponds to the joint 95 12, Figure 4; it is sufficient if it be almost tight and it may be made with or without the interposition of plastic packing material.

Figure 7 is a modification of the arrangement shown in Figure 6 in which the stopper 3 is screwed onto the part 9, instead of being 100 screwed into the socket 6.

In the arrangements shown in Figures 3, 4, 5, 6 and 7 the joint at the mouth of the body of the cylinder is insured by means of a small cylindrical block 4 of more or less plastic material held in the stopper 3; this small block is generally of ebonite.

Figure 8 is a modification of the arrangement illustrated in Figure 6 in which the part 9 inserted in the body of the cylinder, instead of being made of metal, is made of ebonite or like plastic material, while the stopper 3 is entirely of metal, that is to 110 say, being the reverse of the previous arrangements, it has no cylinder 4 of ebonite or like material. This modification enables one part to be dispensed with as well as the plastic washer 11 (Figure 6) and the plastic 115 washer which may be provided at 12 (Figure 6).

In all the arrangements shown the free passage of the gas during filling and discharging is insured by means of holes, 120 grooves, flattened portions or notches formed in the stopper 3 in the ordinary manner.

I claim as my invention:

1. In a device for closing cylinders for compressed or liquefied gas, the combination 125

with the cylinder and the closing cap therefor, of an internally screw-threaded socket, adapted to be screwed on an outer thread provided at the end of the cylinder thus constituting a joint with said cylinder, said socket terminating in an annular portion coaxial with the socket and adapted to provide the required joint for the filling and discharging of the cylinder, said socket having a reduced inner diameter towards its free end, said closing cap being screwed onto a threading provided within said socket between the end of the cylinder and the free end of said socket and adapted to close the mouth of the cylinder, the reduced inner

diameter of said socket forming an abutment for said closing cap, preventing it from being completely removed.

2. The combination as specified in claim 1, in which said cylinder comprises two parts, viz., a cylindrical body part and a neck part provided with a bore, the said two parts being united in an air tight manner by the said socket being screwed onto said body part, a shoulder on said socket engaging said neck part, said closing cap being formed with an outer thread engaging a corresponding inner thread in said socket.

In testimony whereof I affix my signature.
LOUIS LEMOINE.
